UNITED STATES PATENT OFFICE.

HANS DEUTSCH, OF VIENNA, AUSTRIA.

EXHAUST-STEAM INJECTOR.

Application filed January 23, 1926, Serial No. 83,319, and in Austria March 14, 1925.

This invention relates to exhaust steam injectors in which exhaust steam together with a certain quantity of live steam is employed for feeding water into a boiler or

5 other vessel and in which provision is made for substituting live steam for the exhaust steam, whenever such exhaust steam is not available, so as to allow operation of the injector at any time whether or not the engine from which the exhaust steam is derived is running.

In injectors of this kind in order to change from the operation of the injector with combined exhaust and live steam 15 over to operation with live steam alone a change over device or apparatus must be provided and this device or apparatus is generally and especially in the case of locomotives controlled by the steam pressure 20 prevailing in the valve chest of the engine or in the steam feed pipe leading thereto. Now in arrangements of the kind mentioned a certain drawback is experienced when the locomotive or engine is running with the 25 regulator or throttle valve shut and with the injector out of operation, as in this case the variations of the pressure in the valve chest are liable to damage the change over device especially if the pressure is oscillating

30 about the atmospheric line. In this case the valves or pistons influenced by the steam pressure will perform a to and fro movement in accordance with the pressure variations, which will cause the valves to clatter on their seats or in the case of pistons will cause wear of the sealing surfaces, capable of finally impairing the operation of these members which should be in a perfect condition to effect a steam tight sealing.

40 Now according to my invention these defects are avoided by providing the chamber or room containing the change over device and controlled by the steam pressure in the valve chest or steam feed pipe or a chamber 45 communicating therewith or the steam pipe leading to this member with an opening leading to the atmosphere and adapted to be controlled by a nonreturn valve.

Said nonreturn valve in the event of variations of pressure as described prevents the formation of any pressure lower than the atmosphere and therefore also prevents any lifting or other movement of the controlling member, which therefore rests on 55 its seat or remains in its position of rest

without being affected by the pressure variations.

In the accompanying drawings my invention is illustrated by way of example.

Fig. 1 shows a change over device for exhaust steam injectors provided with the air valve and applied to one form of an exhaust steam injector in which the change over from exhaust steam to live steam operation of the injector is effected by a counter valve.

Fig. 2 illustrates the application of the invention to a change over device operated by means of a piston.

Fig. 3 shows a change over device in which the air valve is arranged in the main control pipe of the device.

The injector consists of a number of nozzles as usual among which the live steam nozzle 21, the exhaust steam nozzle 23, the combining nozzle 24 and the delivery nozzle 25 are the most important. The injector is enclosed in a casing 20 provided with the necessary inlet and outlet openings.

4 denotes the inlet for the exhaust steam to the injector, 2 the passage for the high-pressure steam from the boiler flowing into the injector through the inner steam nozzle 21; 3 is a second passage for live steam, through which the boiler steam at a reduced pressure reaches the exhaust-steam nozzle 23; 5 denotes a valve, the upper and larger

seat of which shuts off a chamber 26 from a chamber 27 which communicates with the boiler by way of an opening 28 and an inlet 1. The chamber 26 is adapted to be shut off by means of a valve 6 from a chamber 7 which is connected through the pipe 8 with the steam chest of the engine or with the main steam pipe leading from the throttle-

valve of the engine to the valve chest. 95 When the valve 5 rests against its upper seat it forces the valve 6 off its seat. The upper seat of the valve may also be slightly roughened, or may be caused to leak slightly in some other way, so that small quantities of steam can pass from the chamber 27 into the chamber 26 even when this valve is closed. The chamber 7 or the chamber 9

communicating therewith communicates with the open air by means of an opening 10. 105 A nonreturn valve 11 controlling said opening and which may be arranged to slide within the central guiding portion of valve

6 closes the said communication of the chambers 9 and 7 with the open air, whenever a 110

higher pressure than the atmospheric pressure prevails in the chamber 9.

The device operates in the following manner:

- 6 If the locomotive is running under steam, the pressure which prevails in the chamber 7 will shut the nonreturn valve 11. The pressure which, however, is lower than the full boiler pressure causes small quantities of steam to leak through the seat of the valves 6 or through the small gaps provided therein from the space 26 which communicates with the inlet 1 in which the full boiler pressure prevails by means of the chambers 27 and 26. So long as the difference of pressure and consequently the velocity of flow between the inlet 1 and chamber 7 do not exceed a certain value, the valve 5 will bear against its lower seat and close the auxiliary live steam passage 3, the injector being then operated by the live steam flowing through the conduit 2 and the exhaust steam flowing through the exhaust pipe 4.

When the throttle valve is closed and the engine is consequently running without steam, a drop in pressure takes place in the pipe 8 and also in the chamber 7, causing the velocity of the steam flowing from the inlet 1 to the chamber 7 to increase so that 30 the valve 5 is forced against its upper seat, thus stopping the flow of steam to the chamber 7 and opening the way to the auxiliary live steam passage 34. The injector is then working under live steam alone, the steam 35 flowing through the pipe 3 taking the place of the exhaust steam. At the same time the valve 11 drops on account of its own weight as it is no longer held by the high steam pressure in the valve chest and frees the 40 opening 10, thus admitting atmospheric pressure within the chamber 7. The valves are in this case no longer under the influence of the pressure in the steam chest, which may be variable and oscillates about 45 the atmospheric line.

The live steam flowing through the passage 3 in place of the exhaust steam must be throttled prior to entering the nozzles. If the steam be throttled at the small opening 28 which it passes before reaching the valve 5, a comparatively small pressure will prevail in the chamber 27 owing to the valve 5 being lifted against its upper seat and consequently when the throttle-valve is again 55 opened, even a certain though comparatively slight pressure in the valve-chest above the atmospheric will cause the valve 5 to come down to its lower seat again and to close the passage 3 while at the same time the non-return valve 11 is closed.

According to the arrangement shown in Fig. 2 a piston 12 is provided instead of the valve 6, which is subject to the pressure of the steam in the chamber 37 and fed to this chamber by means of a pipe 38 leading from

the valve chest. The small quantities of steam leaking from the chamber 37 around the piston to the other side owing to the unavoidable defects in the tight seating of the piston would after a certain time 70 cause the steam to be equal at both sides of the piston, whereby the application of the steam chest pressure would be inoperative. In order to prevent such a pressure equalization devices of this kind are always provided 75 with an outlet, such as the pipe 39 shown in the drawing, by means of which these small quantities of steam may escape to the open air, so that in the left side of the cylinder atmospheric pressure is always prevailing. 80 The piston 12 has a diameter that is larger than the diameter of valve 13 and it holds such valve 13 in its closed position and therefore prevents the access of live steam through the pipe 33 to the exhaust steam 85 chamber of the injector whenever exhaust steam is flowing to the same. Pipe 33 is preferably provided with a restricted cross section 34 at the inlet end in order to reduce the pressure of the steam entering 90 through pipe 33 into the exhaust steam nozzle. An opening 30 controlled by a valve 31, which may be ball-shaped, allows to establish communication between the chamber 37 and the atmosphere if no pressure is present in the chamber 37, which presses the ball 31 against said opening 30. If however the exhaust steam injector is not in operation and if for instance the locomotive is running without steam as when running down a hill or when entering a station then variations of pressure will occur 95 in the valve chest which oscillate about the atmospheric line and will cause the pressure periodically to raise above and to fall below the atmospheric pressure. In this case however owing to the communication of the chamber 37 with the atmosphere through the opening 30 the controlling member 12 is not lifted or moved but remains in its position of rest, the injector being at this time 100 out of operation as already explained and the steam supply being therefore shut off.

The construction of the injector according to Fig. 2 is identical to that shown in Fig. 1 and the tubes 32 and 33 in Fig. 2 are joined in the same way to the injector as according to the arrangement shown in Fig. 1.

Fig. 3 shows another modification of the arrangement described with reference to Fig. 1 and controlling an identical injector as that shown in Figure 1. In this case however the opening 40 is not provided at the top of the structure in a chamber 9 as in Fig. 1 but is arranged in a sleeve inserted in 125 the pipe 48, leading to the valve chest. It is shown controlled by a ball shaped valve 41 which will act in the same way as the non-return valves 11 and 31 of the modification shown in Figure 1 or 2 and will close the 130

opening when a higher pressure than the atmospheric is prevailing in the pipe or the chamber 47, but will free the opening as soon as the pressure in said pipe is equal or 5 lower than the atmospheric pressure. Otherwise the construction and operation is identical with that described with reference to Fig. 1 and corresponding reference letters are used to denote identical parts.

10 What I claim is:

1. In an exhaust steam injector of the kind specified adapted to be worked by the exhaust steam of an engine, an exhaust steam nozzle adapted to be alternately fed by an 15 exhaust steam branch and by an auxiliary live steam branch, an automatic change over device controlling the admission of steam to said auxiliary live steam branch and making said branch operative when the working 20 steam for the engine is cut off from the engine, said change over device comprising cooperating members one of which being operated by the working steam pressure within a pressure system, consisting of a chamber and 25 a steam admission branch carrying steam of the working pressure of the engine, one of the parts of said pressure system being provided with automatic means controlling the admission of atmospheric pressure to said 30 system and admitting atmospheric pressure whenever the supply of working steam to the engine is cut off.

2. In an exhaust steam injector of the kind specified adapted to be worked by the exhaust steam of an engine, an exhaust steam nozzle adapted to be alternatively fed by an exhaust steam branch and by an auxiliary live steam branch, an automatic change over device controlling the admission of steam to 40 said auxiliary live steam branch and making said branch operative when the working steam for the engine is cut off from the engine, said change over device comprising cooperating members controlled by the pressure of the live steam and by the pressure of 45 the working steam of the engine, the last named controlling means comprising a chamber communicating with a steam pipe carrying steam of the working pressure and

with the atmosphere by means of an opening and a non-return valve controlling said opening.

3. In an exhaust steam injector of the kind specified adapted to be worked by the exhaust steam of an engine, an exhaust steam nozzle adapted to be alternatively fed by an exhaust steam branch and by an auxiliary live steam branch, an automatic change over device controlling the admission of steam to 50 said auxiliary live steam branch and making 55 said branch operative when the working steam for the engine is cut off from the engine, said change over device comprising cooperating members one of said members being a valve actuated by the live steam pressure and the second member being arranged within a chamber adapted to be set into communication with some part of the engine containing steam of the working pressure when the engine is working, said chamber 60 being provided with an opening and said opening being controlled by a non-return valve adapted to close said opening when steam of working pressure is admitted and to 65 open it when steam of working pressure is 70 cut off from the engine.

4. In an exhaust steam injector of the kind specified, a change over device according to claim 1, wherein said change over device comprises two valves, one valve being 75 capable to lift the other valve and being provided with two seats, one seat controlling the admission of live steam to the auxiliary steam pipe and the other valve being arranged in a chamber adapted to be set in to 80 communication with some part of the engine containing steam of the working pressure of the engine and with the atmosphere, the latter communication being controlled by a non-return valve adapted to be actuated by 85 the admission of steam of the working pressure to said chamber and opening the communication with the atmosphere when the steam is cut off from the engine.

In testimony whereof I have hereunto set 90 my hand.

HANS DEUTSCH.
